US00D772172S

(12) **United States Design Patent** (10) **Patent No.:** **US D772,172 S**
(45) **Date of Patent:** **** Nov. 22, 2016**

(54) **SIGNAL I/O MODULE**

- (71) Applicant: **YOKOGAWA ELECTRIC CORPORATION**, Musashino-shi, Tokyo (JP)
- (72) Inventors: **Naoto Takano**, Musashino (JP); **Noriaki Senba**, Musashino (JP); **Kouichirou Shimamura**, Musashino (JP); **Hiroki Kuraishi**, Musashino (JP)
- (73) Assignee: **YOKOGAWA ELECTRIC CORPORATION**, Tokyo (JP)
- (**) Term: **14 Years**
- (21) Appl. No.: **29/497,558**
- (22) Filed: **Jul. 25, 2014**

(30) **Foreign Application Priority Data**

- Jan. 29, 2014 (JP) 2014-001708
- (51) LOC (10) Cl. 13-03
- (52) U.S. Cl. USPC D13/162; D13/147
- (58) **Field of Classification Search**
USPC D13/123, 133, 146, 147, 149, 154, D13/162.1, 184, 199; 439/74, 108, 180, 439/252, 258, 246, 278, 374, 378-379, 381, 439/527, 529, 533, 660, 717, 865-894, 953, 439/135, 144, 139-141, 147, 136, 638, 518, 439/131, 271; 174/16.3; 257/697, 727; 361/769; D14/435, 356, 242, 436, 433, D14/474, 240, 496, 385, 358, 480.1-480.7, D14/125, 388, 203.4; 360/97.01, 685-686, 360/752, 737, 732, 784, 803; 365/51, 63, 365/131; 710/52, 300, 313; 711/115, 103, 711/154, 161-162; 70/58; 323/210; 713/186, 1; 382/124

(57) **CLAIM**

The ornamental design for a signal I/O module, as shown and described.

DESCRIPTION

FIG. 1 is a front perspective view of a signal I/O module showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof in use.

The broken lines shown are included for the purpose of illustrating the unclaimed portions of the signal I/O module and form no part of the claimed design.

1 Claim, 6 Drawing Sheets
